UNITED STATES PATENT OFFICE.

VOLNEY P. KELLER, OF MALVERN, PENNSYLVANIA.

EXCAVATOR.

1,094,215.

Specification of Letters Patent. Patented Apr. 21, 1914.

Application filed March 17, 1910. Serial No. 549,945.

To all whom it may concern:

Be it known that I, VOLNEY P. KELLER, a citizen of the United States, residing in Malvern, Chester county, Pennsylvania, have invented certain Improvements in Excavators, 5 of which the following is a specification.

My invention consists of certain improvements in the excavator for which I obtained Letters Patent of the United States, No. 760,996, on the 24th day of May, 1904, the 10 object of my present invention being to provide for the better support of the rotary excavator and projecting frame at the bow of the scow or barge, to concentrate, in a more 15 effective manner than before, the force of the forwardly projected streams of water upon the bank which is being cut away, and to so construct the hull of the scow or barge as to provide for the rigid support of the 20 various engine structures carried thereby. These objects I attain in the manner hereinafter set forth, reference being had to the accompanying drawing, in which—

Figure 1 is a view, partly in side elevation 25 and partly in section, of an excavator constructed in accordance with my present invention, and Fig. 2 is a plan or top view of all of the parts with the exception of the rotary cutter which is shown in horizontal 30 section.

The excavator, in its general construction, is similar to that forming the subject of my former Letters Patent and comprises a scow or barge 1 upon the sides of which are pivotally mounted forwardly projecting arms 2 which support a frame 3 and carry the bearings for the shaft 4 of a rotary excavator, the purpose of the latter being to dig a canal in which the barge floats or to deepen a 35 canal already dug, the spoil, as it is dislodged by the action of the cutter, being carried away from the canal by the action of powerful forward currents of water generated by the action of propellers 5 at the bow 40 of the scow.

An objection to the former type of excavator was the difficulty of properly supporting the projecting frame, the cutter and its operating mechanism which caused such 50 an excess of weight at the bow of the scow that, when the supporting arms 2 were locked to the hull, the buoyancy of the latter was not sufficient to properly support the projecting bow structure and cutter, the 55 scow or barge being drawn down by the head and the cutter pressed against the bot-

tom of the canal, with the result that the cutting operation was not uniform and the bottom of the canal was not maintained at the same level. I overcome this objection 60 by making the body of the cutter in the form of an air and water tight drum 6, which possesses sufficient buoyancy to support the overhanging bow structure of the barge and permits me to regulate the depth 65 and character of the cut in such manner that the depth of cut is uniform at all times, the buoyancy being so proportioned to the weight that uniform pressure of the cutter upon the bottom of the canal can be readily 70 maintained.

The drum 6 has mounted upon its exterior, a series of projecting rings 7 which carry the cutting blades 9, the central ring also carrying a toothed gear ring 10, with 75 which engages a driving chain 11, adapted to a toothed wheel 12 on a shaft 13 mounted in bearings on the top of the frame 3, as shown in Fig. 1, this shaft having a pulley 14 for the reception of a driving belt 15 80 from the engine 16, mounted upon the hull of the scow and employed for the purpose of imparting a rotating movement to the cutter.

The projecting frame 3 also carries a deflector 17 located in advance of the cutter 85 and it provides bearings for a shaft 19 having windlasses 20 upon which are wound cables 21, suitably anchored in advance of the scow, so that, by turning said windlasses, the scow can be drawn ahead as the cutting 90 of the canal progresses.

Each of the propellers 5 is carried by a shaft 22 extending to an engine 23 mounted on the hull of the barge and each propeller 5 is contained in a channel-way in a funnel 95 24, carried by a transverse partition 25 at the bow of the barge, the lower portion of said partition carrying a forwardly and downwardly projecting apron 26 which may, if desired, be so mounted that its forward 100 end can be raised or lowered in order to determine, in a measure, the direction of the currents of water projected forwardly by the propellers 5.

The end rings 7 of the drum 6 serve to 105 confine within the lateral limits of the cutter, the streams of water projected forwardly by the propellers 5, and the intervening rings 7 serve to subdivide and direct these streams so that the force of the 110 latter is wholly concentrated upon the bank upon which the cutters are acting, any lat-

eral deflection of the streams of water before they reach said bank being effectually prevented and the subdivision of the streams insuring substantially uniform action of the water throughout the entire width of cut.

As the rotary cutter is not now dependent for its support upon the buoyancy of the hull of the scow, the provision formerly adopted for locking the projecting arms 2 to 10 the hull of the scow may, if desired, be dispensed with, although it is preferable to use them, in order that the buoyancy of the scow may, if occasion requires, be added to that of the drum 6, as a means of supporting 15 the cutter.

In order to provide a rigid support for the engine 16 which drives the cutter, said engine is mounted directly upon transverse beams 27 which constitute part of the struc-

20 tural frame work of the hull of the scow, and, for the same reasons, the propeller-driving engines 23 are mounted upon longitudinal beams 29 carried by transverse beams 30 which also constitute part of the struc- 25 tural framework of the scow, the cutter-rotating engine having its cylinders disposed athwartships of the scow and the propeller driving engines having their cylinders disposed in fore-and-aft lines.

30 The arms 2 carry depending aprons 31 which serve to prevent lateral escape of the currents of water in their passage from the propellers 5 to the rotary cutter and the lower apron 26 is hinged at 32 to these side 35 aprons, whereby, as the arms 2 are raised or lowered, the forward edge of the apron 26 will be raised and lowered accordingly, the partition 25 being sufficiently flexible to permit such movement, and said edge will 40 therefore always preserve the same relation to the bottom of the rotary cutter.

I claim:

1. The combination, in an excavator, of a scow, a water tight drum in advance of the 45 hull of the scow, transverse cutters carried by said drum and providing spaces between the same and the drum, means for causing a forwardly flowing current of water to pass

under the drum and through the spaces between the same and the cutters, and means 50 for confining said current of water within the lateral limits of the drum.

2. The combination, in an excavator, of a scow, a water tight drum located in advance of the hull of the scow, transverse 55 cutters carried by said drum and providing spaces between the same and the drum, means for causing a forward flow of water underneath the drum and through the spaces between the same and the cutters, means for 60 confining said flow of water within the lateral limits of the drum, and means for subdividing such flow of water within such limits.

3. The combination of a scow, a rotary 65 cutter in advance of the same, means for causing forwardly flowing currents of water through said cutter, and side aprons for preventing lateral escape of the water on its way to the cutter. 70

4. The combination of a scow, a rotary cutter in advance of the same, pivoted and vertically movable arms carrying said cutter, means for causing forwardly flowing currents of water through the cutter, and 75 side aprons secured to the cutter carrying arms and serving to prevent lateral escape of the water on its way to the cutter.

5. The combination of a scow, a rotary cutter in advance of the same, a vertically 80 movable support for said cutter, means for causing forwardly flowing currents of water through the cutter, a lower apron for directing said currents of water to the cutter, and side aprons having pivotal connection with 85 said lower apron and carried by the vertically adjustable cutter support, said aprons serving to prevent lateral escape of the water on its way to the cutter.

In testimony whereof, I have signed my 90 name to this specification, in the presence of two subscribing witnesses.

VOLNEY P. KELLER.
